UNITED STATES PATENT OFFICE.

GEORGE D. HECK, OF PRINCE BAY, NEW YORK, ASSIGNOR TO THE S. S. WHITE DENTAL MANUFACTURING COMPANY, A CORPORATION OF PENNSYLVANIA.

SPITTOON.

Application filed August 9, 1918. Serial No. 249,041.

To all whom it may concern:

Be it known that I, GEORGE D. HECK, a citizen of the United States, and a resident of Prince Bay, in the county of Richmond,

5 State of New York, have invented certain new and useful Improvements in Spittoons, of which the following is a specification, reference being had to the accompanying drawings.

10 My invention relates particularly to fountain or flush spittoons, and is especially directed to spittoons having an attachment for a saliva ejector, and adapted for use of dentists, physicians, surgeons, etc.

15 The principal objects of my invention are, to provide a spittoon with a saliva ejector arranged to be discharged directly into the waste-pipe connections and to provide means to noiselessly release and discharge any air 20 that may be trapped in the waste connections, and to direct the moisture-laden air thus released into the spittoon bowl.

Other objects of my invention are, to provide means to automatically seal the passage-way between the waste-pipe connections and the saliva ejector when the latter is not in use, and arranged to be opened by the flow of water which actuates said saliva ejector.

30 My invention comprehends a novel arrangement of the valves and passages connecting the valve-head with the waste connections, and also includes means adjustable to limit the opening movement of said valves.

35 Specifically stated, the form of my invention as hereinafter described, comprises a passage-way leading from the saliva ejector into the waste-pipe connections and including a check-valve therein arranged to automatically open when the saliva ejector is in use, and to close when said use is terminated; a vent for the escape of trapped air in said waste-pipe connection; a deflector for diverting splashed water away from said vent; and also comprises a spring pressed lever 40 adapted to engage a suitable notch in the valve handle to limit the rotation of the valve in its opening movement, and arranged to permit the free rotation of said valve in its closing movement.

My invention also includes all of the various novel features of construction and arrangement as hereinafter more definitely specified.

In the accompanying drawings, Figure 1 55 is a sectional elevation of the spittoon with its mounting and attachments; Fig. 2 is a fragmentary sectional view of said spittoon and its attachments on a larger scale; Fig. 3 is a front elevational view of the supply 60 valve-head shown on a still larger scale; and Fig. 4 is a sectional elevational view taken on the line 4—4 in Fig. 3, showing fragments of the bowl arm and bowl.

In said figures the bowl bracket 1 is carried in the usual manner by the crane standard 2, and at its free end supports the bowl arm 3 extending oppositely from its waste outlet 5, which extends through the downwardly depended threaded nipple 6 rotatably 70 mounted in a suitable bearing 7 in the free end of said bracket 1.

The oppositely disposed extensions of the bowl arm 3 comprise inlets 9 and 10 from the bowl 11 and tumbler-holder 12, respectively. Said bowl 11 is conveniently connected with the inlet 9 of the bowl arm 3 by the collar 13, which carries the reticulated strainer trap 14, having the funnel 15, and which is provided with the threaded extension 16 depending into the inlet 9, in threaded engagement with the bowl arm 3. The other extension comprising the inlet 10, of the bowl arm 3, projects laterally and upwardly beyond the periphery of the bowl, terminating in the pocket 17 local to the inlet 10, which pocket affords a water seal for the tumbler-holder 12.

Said tumbler-holder 12 is provided with a collar 20 in threaded engagement with the hollow standard 21, which is detachably connected by the set-screw 22 with the inlet 10 and which has a tubular extension 23 depending into the water 24 in the pocket 17 to form a trap for preventing undesirable sounds and gases from the waste-pipe connection escaping through said tumbler-holder.

The bowl arm 3 carries the valve-head 25 comprising the valve 26 having the handle 100

27 for controlling the water supply to the tumbler 29 (shown in dot and dash lines in Fig. 2), in the tumbler-holder 12; the valve 30 having the operating handle 31 for controlling the water supply to the spittoon bowl 11, and the valve 32 having the operating handle 33 for controlling the water supply in connection with the saliva ejector to be hereinafter described.

10 The valve-head 25 is connected with the nipples 35, 36 and 37, on the bowl arm 3, by the unions 38, 39 and 40, respectively comprising the union nuts 41, 42 and 43, through which the various passage-ways 15 leading from the water distributing chamber 45 in the valve-head 25 and controlled by the valves 26, 30 and 32, respectively, extend, the water being supplied to said water distributing chamber 45 by the water supply 20 pipe or tube 44.

The valve 26 has the plunger 46, cooperatively related with the valve seat 47, and controls the passage-way from the water chamber 45 in the valve-head 25, to the 25 tumbler 29, comprising the union 38, tubular conduit 48, leading upwardly through the hollow standard 21 and connected through the side of said standard with the goose-neck 49 for directing water into the 30 tumbler 29, from which the overflow flows into the dished tumbler-holder 12, through the hollow standard 21 and into the waste-pipe connections through the inlet 10 and arm 3.

35 The valve 30 is provided with a plunger 50 cooperatively related with the valve-seat 51, and controls the passage-way leading from the chamber 45 in the valve-head 25, to the spittoon bowl 11, comprising the duct 52, union 39, nipple 36, duct 53, plug 54, union 55, goose-neck 56, and nozzle 57 discharging into the bowl 11.

The valve 32 for controlling the saliva 45 ejector (not shown), is provided with the plunger 59 cooperatively related with the valve-seat 60, and controls the passage-way leading from the chamber 45 in the valve-head 25, into the bowl arm 3, through the 50 duct 61, nozzle 62 of the injector 63, duct 64, union 40, and port 65, into the bowl arm 3. Said injector 63 is removably connected in screw-threaded relation with the valve-head 25, and comprises the slotted head 66 by 55 which it may be rotated by a screw-driver, into or out of its operative position, or removed therefrom if desired.

The saliva ejector, (not shown) is connected by the flexible tubing 69, through the union 70 comprising the union nut 71, and 60 duct 72 in the nipple 73 and valve-head 25, with the duct 64 into which said duct 72 leads, adjacent to the outlet end of the nozzle 62 of the injector 63, so that when the valve 32 is opened, water from the valve-head 25 is directed through the injector and

into the bowl arm 3, thereby forming a suction in the saliva ejector tube to draw saliva therethrough and discharge it directly into said bowl arm 3 and the waste-pipe connections attached thereto.

The passage-way leading through the union 40 is conveniently provided with a check valve 75 having the guiding stem 76 extending through said union, and having the conical intermediate surface cooperative 75 with the end of said union as a valve-seat to automatically close said passage-way when the valve 32 is closed and the saliva ejector is not in operation, to prevent undesirable 80 gases from the waste-pipe connections entering the saliva ejector tube and parts connected therewith. As shown in Fig. 4. the check valve 75 is limited in its upward movement by the pin 77 extending transversely 85 across the passage-way in the nipple 36.

The valve 32 also controls the duct 79 leading to the nipple 80 and union 81 to which the flexible tube 82 is connected for directing water to a syringe or other suitable device, (not shown), which may be attached to the free end of said tube 82.

It will be obvious that the saliva ejector tube will carry considerable aerated fluid into the bowl arm and waste-pipe connections, and therefore, said bowl arm is provided with the vent outlet passage-way 83, which is restricted by the plug 54, whose one side is cut away, as shown at 85 in Fig. 4, to provide a restricted vent for the free escape of any air that may be trapped in said bowl arm. Said vent outlet passage-way 83 is connected by the tubular extension 86 which has its outlet orifice directed into the spittoon bowl 11, and preferably conforms to the goose-neck 56 by which it is conveniently carried.

It has been found in practice that there is a tendency, especially with the juvenile patients, to maliciously turn on the valve leading to the tumbler and thereby unduly overflow the same, and to prevent such action, the valve 26 is provided with a spring pressed lever 89 arranged to be maintained by the spring 90, either in its inoperative position shown in dotted lines, or in its operative position as shown in full lines, and arranged to engage the shoulder 91 on the rotary valve-handle 27, in the anti-clockwise or opening movement of the valve-handle 27, to limit the flow of water from the chamber 45 through said valve into the passage-way leading to the tumbler. Said valve-handle 27 is provided with the edge 93 disposed opposite to said shoulder 91, and arranged to ride under the lever 89, affording a free movement of the valve-handle 27 in a clockwise or closing movement to close the valve 26.

As it is desirable that the flow of water into the tumbler may be varied, the valve-

head 27 is arranged to be rotatably set with respect to its plug 46 by the set screw 94 as best shown in Fig. 2.

The valve-head 25 is conveniently provided with the outer cover plate 95 which is removably attached to the bowl arm 3 by the screws 96, and which conveniently carries the lever 89 and its spring 90.

The plug 54 shown in Figs. 1, 2 and 4, is 10 of a diameter substantially equal to the transverse dimension of the bowl arm, local to said plug, and said plug is provided with a depending apron or extension 97 serving as a deflector, arranged to divert any waste 15 or splashed water coming from the tumbler-holder or saliva ejector that might be so splashed as to enter the vent outlet 83, and sputter forth from the discharge orifice of said outlet.

20 The tumbler-holder 12 is bowl-shaped, having the internal radially disposed ribs 98, which have their central portions offset to provide shoulders 99 between which the tumbler 29 may rest upon the offset portions 25 of said ribs.

Water is admitted through the supply tube 44 into the chamber 45 in the valve-head 25, and the flow of water in the spittoon bowl 11 is controlled by the valve 30, whose plunger 30 50 is arranged to be engaged with or be retracted from its valve seat 51 by rotation of the handle 31, to control the flow of water to said bowl 11, through the passage-way comprising the bore 52, union 39, bore 53, 35 union 55, goose-neck 56 and nozzle 57. The flow of water to the tumbler is conveniently controlled by the valve 26 whose plunger 46 may be engaged with and retracted from its seat 49 by rotation of the valve-handle 27, 40 to control the flow of water from the chamber 45 through the passage-way comprising the union 38, nipple 35, tubular conduit 48, and goose-neck 49 into the tumbler, the overflow of which is caught by the tumbler- 45 holder 12 and carried by the hollow tubular standard 21 through the trap 17 into the inlet 10 and the bowl arm 3 and away through the waste-pipe connections.

The flow of water for actuating the saliva 50 ejector is controlled by the valve 32 whose plunger 59 may be engaged with and retracted from its seat 60, by rotation of the valve-handle 33, to control the flow of water from the chamber 45 through the duct 61 55 nozzle 62, duct 64, union 38, and outlet aperture 65, into the bowl arm 3, and as will be obvious, the force of the water from the nozzle 62 will form such suction in the duct 72 and flexible tubing 69 as to draw saliva therethrough from the saliva ejector into the bowl arm 3 from where it is discharged through the wastepipe. When said valve 32 is open, water leading to a syringe or other suitable device is admitted through the duct 60 79 and flexible tube 82 under pressure.

I do not desire to limit my invention to the precise details of construction and arrangement as herein set forth, as it is obvious that various modifications may be made therein without departing from the essential features of my invention as defined in the appended claims.

Having thus described my invention, I claim:

1. A spittoon of the class described, having a waste-pipe outlet, a saliva ejector having its discharge outlet leading directly into said waste-pipe outlet, and means automatically actuated to prevent gases flowing back into said saliva ejector when not in use. 75

2. A spittoon of the class described, having a waste-pipe outlet, a saliva ejector having a discharge outlet leading directly into said waste-pipe outlet, and a check valve for preventing back flow toward said saliva 85 ejector.

3. A spittoon of the class described, having a waste-pipe outlet, a saliva ejector having its discharge outlet leading directly into said waste-pipe outlet, a check valve in said 90 saliva ejector outlet, an injector leading into said saliva ejector outlet, and a valve for controlling said injector.

4. A spittoon of the class described, having a waste-pipe outlet, a vent for said 95 waste-pipe outlet, a saliva ejector having its discharge outlet leading directly into said waste-pipe outlet, and a valve for controlling said saliva ejector.

5. A spittoon of the class described, having a waste-pipe outlet, a saliva ejector having its discharge outlet leading directly into said waste-pipe outlet, a vent for said waste-pipe outlet leading into the spittoon bowl, and a deflector arranged to prevent splashed 105 water from entering said vent.

6. A spittoon of the class described, having a waste-pipe outlet, a saliva ejector having its discharge outlet leading directly into said waste-pipe outlet, a vent for said waste-pipe outlet leading into the spittoon bowl, a plug extended through said vent and forming a restricted passage-way, and having a 110 depending extension forming a deflector to prevent splashed water from entering said vent.

7. A spittoon of the class described, having a waste-pipe outlet, an injector having its nozzle arranged to discharge directly into said waste-pipe outlet, a saliva ejector 120 arranged to discharge into said waste-pipe outlet, and connected adjacent to said nozzle, and a check valve arranged to be opened by the flow of water through said nozzle and automatically closed to prevent the 125 escape of gases from said waste-pipe outlet into the passage-way leading to said saliva ejector.

8. A spittoon of the class described, having a waste-pipe outlet, a saliva ejector hav- 130

ing its discharge outlet leading directly into said waste-pipe outlet, a valve for controlling said saliva ejector, a vent for said waste-pipe outlet comprising a goose-neck 5 leading into the spittoon bowl.

9. A spittoon of the class described, having a waste-pipe outlet, a spittoon bowl connected with said waste-pipe outlet, a saliva ejector arranged to discharge directly into 10 said waste-pipe outlet independently of said spittoon bowl, a goose-neck leading into said bowl and arranged to direct water thereinto, and a vent having a goose-neck conforming substantially to the first-mentioned goose-neck and having its outlet end 15 directed into said bowl.

10. A spittoon of the class described, comprising a spittoon bowl, a hollow bowl arm having a waste-pipe outlet, a valve-head 20 detachably connected with said bowl arm, a saliva ejector valve in said valve-head having a passage-way leading directly into said bowl arm, an injector having a nozzle disposed in said passage-way, a saliva ejector 25 tube connected with said passage-way between said nozzle and bowl arm, and a check valve interposed between said nozzle and said bowl arm.

11. A spittoon of the class described, comprising a spittoon bowl, a hollow bowl arm having a waste-pipe outlet, a tumbler-holder having a hollow standard connected with 30 said bowl arm, a detachable valve-head carried by said bowl arm, a valve in said valve-head having a passage-way leading to the tumbler in said tumbler-holder, a valve in 35 said valve-head having a passage-way leading into the spittoon bowl, and a valve in said valve-head having a passage-way leading 40 directly into said bowl arm, an injector having a nozzle in the passage-way leading to the bowl arm, and a saliva ejector having an inlet connected in acute angular relation 45 to the passage-way adjacent to said nozzle.

45 12. A spittoon of the class described, comprising a spittoon bowl, a hollow bowl arm supporting said spittoon bowl, and provided with an extension projecting outwardly and upwardly beyond said bowl, and having 50 separate passage-ways respectively forming a vent for said bowl arm, and an inlet forming a pocket, a tumbler-holder having an overflow connection leading into said inlet and depending into said pocket and afford- 55 ing a trap, a valve-head detachably connected with said bowl arm, a valve controlling a passage-way leading through said overflow connection, and having a goose-neck leading into the tumbler in said tumbler-holder, a 60 valve controlling the passage-way leading through said valve-head and connected with the passage-way leading through said bowl arm, and connected with a goose-neck hav-

ing its outlet orifice directed into said spittoon bowl, a valve controlling a passage-way 65 leading through said valve-head and having a connection with a port directly opening into said bowl arm, an injector removably disposed in the last mentioned passageway in said valve-head, having a nozzle directed 70 toward said port, and a saliva ejector adjacent to said nozzle with said port.

13. A spittoon of the class described, comprising a spittoon bowl, a hollow bowl arm extended laterally and upwardly and terminating in an inlet having a pocket for containing water, a tumbler-holder supported by said bowl arm, and having a tubular connection provided with an extension projecting into said pocket, forming a trap. 75

14. A spittoon of the class described, comprising a spittoon bowl, a hollow bowl arm extended laterally and upwardly and terminating in an inlet having a pocket for containing water, a tumbler-holder supported by said bowl arm, and having a tubular overflow outlet connection provided with an extension projecting into said pocket, forming a trap, a valve-head detachably connected with said bowl arm, a water supply passage-way leading upwardly through the overflow outlet of said tumbler-holder, and comprising a goose-neck having its outlet orifice directed into the tumbler in said tumbler-holder, and a valve in said valve-head arranged to control said passage-way. 90

15. A spittoon of the class described, comprising a spittoon bowl, a hollow bowl arm having a waste-pipe outlet and a vent outlet, a water supply connection, and a goose-neck having separate passage-ways leading 100 into the bowl and respectively connected with said vent outlet and said water supply connection.

16. A spittoon of the class described, comprising a spittoon bowl having a waste-pipe outlet, a water supply connection, and a conduit having separate passage-ways arranged to discharge into said spittoon bowl and respectively connected with said waste-pipe outlet and with said water supply connection. 110

17. A spittoon of the class described, comprising a spittoon bowl having a trap leading to a waste pipe outlet, a vent leading from said waste-pipe outlet into the spittoon bowl to relieve trapped air, and a deflector arranged to protect the vent and thereby prevent splashed water from entering said vent. 115

In witness whereof, I have hereunto set my hand this 17th day of July, 1918.

GEORGE D. HECK.
